UNITED STATES PATENT OFFICE.

CHARLES C. BLAKE, OF BROOKLINE, MASSACHUSETTS.

MACHINE FOR MAKING INSULATED NAILS.

Application filed March 4, 1922. Serial No. 541,114.

To all whom it may concern:

Be it known that I, CHARLES C. BLAKE, a citizen of the United States, residing at Brookline, in the county of Norfolk and State of Massachusetts, have invented certain new and useful Improvements in Machines for Making Insulated Nails, of which the following is a specification.

This invention relates to machines for making insulated nails of the type disclosed in Letters Patent of the United States No. 1,366,661 dated June 30, 1920 to Bennett G. Jansson, and more particularly to improvements in the machine for making such nails disclosed in my Patent No. 1,411,951, April 4, 1922.

In said prior machine means is provided for feeding two of the three elements comprising the insulated nail, namely a wire nail and a wood block, to a rotary turret on which they are assembled and then carried to a capping station. At the capping station the wood block is compressed on the wire nail and is bound in compressed condition by application of the third element of the nail, namely a fibre cap. The completed nail is then ejected. The general principles of the machine of said patent are embodied in the machine of the present invention, the object of the invention being to improve the operation of the prior machine in certain particulars. To this end certain novel features of the present invention relate to improved mechanism for transferring and assembling the several elements of the nail, the means for supplying these elements to the machine being the same as is disclosed in said patent. Other novel features, which will readily be recognized by those skilled in the art, will be apparent from the following description.

To the accomplishment of the object named the invention comprises the features, combinations and arrangements of parts hereinafter set forth, the preferred form of the invention being illustrated in the accompanying drawings, in which:

Figure 1 is a front elevation of the working parts of the machine; Fig. 2 is a rear elevation of the parts shown in Fig. 1, but showing in addition the driving mechanism; Fig. 3 is a vertical section, in left side elevation, through the nail-delivering and capping stations; Fig. 4 is a detail, in sectional plan, of the nail transferring and fibre strip feeding mechanisms; Fig. 5 is a detail, in

left side elevation, of the parts shown in Fig. 4; Fig. 6 is a section, in plan, of the plunger mechanism at the block transferring center punching and nailing stations, Fig. 7 is a sectional detail of the block transferring station; Fig. 8 is a sectional detail of the center punching station; Fig. 9 is a sectional detail of the nailing station; Fig. 10 is a sectional detail of the capping station before the cap has been dinked from the fibre strip; Fig. 11 is a sectional detail of the capping station after the cap has been dinked and the assembled nail and block delivered to this station; Fig. 12 is a sectional detail of the capping station showing the cap being formed; Fig. 13 is a sectional detail of the capping station showing the insulated nail completely formed; Fig. 14 is a sectional detail of the capping station showing the ejection of the insulated nail; and Fig. 15 is a detail in sectional elevation of the insulated nail made by the machine.

The insulated nail (Fig. 15) produced by the machine embodying the features of the present invention comprises a nail 1 having a wooden cleat 2 thereon which is provided with a seat 3 to facilitate its passage between a pair of telephone wires 4. The cleat 2 is compressed upon the nail 1 and is bound in compressed condition on the nail by a binder or cap 5 molded from a disk of fibre.

Referring now to Figs. 8 to 14 for a preliminary general description of the machine for making the insulated nail illustrated in Fig. 15, the three materials used in making the insulated nails, namely, the nails 1, the cylindrical wooden blocks for the cleats 2, and the fibre for the caps 5, are stored in storage stations from which they are drawn as needed and assembled at a forming station where the three parts of the insulated nail are united. To this end the machine is provided with a rotary turret 6, the construction of which will presently be described, having ten pockets 7 therein (Fig. 3). The turret 6 is rotated in a step by step manner to register each of the pockets 7 successively with an opening 8 at a block inserting station A (Figs. 4 and 7). The inserted block 2 is carried during the next rotative movement of the turret 6 to a block center-punching station B (Figs. 4 and 8) where the block 2 is punched at 9 to accurately determine the position of the nail 1 which is driven through the block 2 at a nail-driving station C (Figs. 4 and

105 110

9) which the block reaches at the end of the second rotative step of the turret 6. At the end of the seventh rotative step of the turret 6 the block and nail are registered 5 at the nail forming station D (Figs. 4 and 10 to 14). At the station D the block and nail are positioned within a die holder 10 having supporting ways 11 for a strip of fibre 12 (Fig. 10). The die holder 10 is 10 provided with a dinker 13 which dinks out a disk or cap 5 (Fig. 11) from the strip of fibre. The dinker 13 is normally held elevated to clear the strip of fibre by a coiled spring 14 and is depressed to dink out the 15 cap 5 by a plunger 15 having a button-shaped cavity 16 therein which co-operates with the upper end of the dinker to form a die cavity 18. After the cap 5 is dinked out of the strip of fibre by the dinker 13 20 a hollow plunger 19 (Fig. 11) is elevated and lifts the block with its contained nail out of the pocket 7 and pushes the assembled cap, block and nail up through the restricted throat 17 of the dinker (Fig. 12). During 25 this movement of the plunger 19 the cap 5 is provided with a circumferentially depending skirt molded over the top of the block 2 into the wood of which it slightly sinks (Fig. 12). Thereafter continued elevation of the plunger 19 forcibly pushes the nail, block and molded cap into the die cavity 18 (Fig. 13) thereupon the block is 30 compressed upon the nail and molded within the depending skirt of the cap. At the same time the upper end 20 of the plunger 19 forms the seat 3. The plunger 15 is then elevated and an ejector 21 is pushed up through the plunger 19 to eject the formed 35 insulated nail from the machine (Fig. 14). 40 The turret 6 (Fig. 4) moves during its rotative movement over the upper end of a long bearing 23 (Fig. 3) formed in an extension piece of a vertical girder 24 having at its lower end a horizontal plate 25 (Fig. 2) bolted to the top of a table 26. The turret 6 is secured to the upper end of a vertical shaft 28 journaled in the bearing 23 and another bearing 29 (Fig. 1) formed 45 on a girder 30 bolted to the bottom of the plate 25. At its lower end the shaft 28 carries a pin wheel 31 (Fig. 2) which is driven intermittently by an irregular worm 32 on a short shaft 33 journaled in the 50 girder 30. The shaft 33 carries a bevel gear 34 which meshes with a similar gear 35 at the lower end of a vertical cam shaft 36 journaled in the girders 24 and 30. The shaft 36 is provided with a pulley (not 55 shown) below the bevel gear 35, which is rotated from a counter shaft journaled in bearings carried by the table 26, driven from an electric motor. The rotation of the countershaft is controlled by a clutch, under 60 control of the operator, all as illustrated and described in said patent hereinbefore re-

ferred to. With these connections the turret 6 is rotated in a step-by-step manner to register the pockets 7 successively with the station A, where the blocks 2 are inserted.

To this end the machine is provided with 70 a block transferer 51 (Figs. 5, 6 and 7) which lifts the blocks 2 one at a time, from a chute 52 and inserts them in the pocket 7 of the turret 6 which is registered with the opening 8 (Fig. 7). The opening 8 functions as a guideway between the lower end of the raceway and the under side of the turret, and is formed in a block 38 secured to a bracket 39 on the girder 24. The block 38 provides a terminal for the end of the 80 block raceway. The block transferer 51 is secured to a slide 53 (Fig. 6) mounted to slide in ways formed on the girder 24 beneath gibs 54. The slide 53 is connected by 85 a link 55 (Fig. 1) to one end of a lever 56 pivoted on a stud 57 supported by a bracket 58 (Fig. 2) secured to the bearing 23. The other end of the lever 56 is provided at its free end with a roll 60 engaging a cam 90 groove 61, formed in the peripheral face of a disk 62 on the shaft 36 and shaped to give the proper reciprocating movement to the transferer 51 through the connections described. The block chute 52 is kept full 95 of blocks by means of a block separating and delivering mechanism 152 (Figs. 1 and 2) in all respect like that described and claimed in my co-pending application Ser. No. 510,768 filed Oct. 27, 1921 now Patent No. 1,511,258, Oct. 14, 1924. At each withdrawal of the transferer 51 a block is 100 delivered to the position of the block 2 in Fig. 7 ready to be delivered to the turret on the next advance of the transferer.

The machine as described thus far, is the same as the machine of said Patent No. 1,411,951 except for the construction of the turret 6 and the mode of carrying the blocks 2 from station to station for the successive operations which eventually form the insulated nail. This novel construction and mode of operation will now be described.

The rotary turret 6, (Figs. 3 and 4) comprises a base plate 63 driven on the upper end of the shaft 28, a supporting block 64, having a peripheral rabbet, pinned to said shaft, and a pocket holding ring 65 fitted into said rabbet. The pockets comprise thimbles 66 seated in each of the ten vertical bores in the ring 65, the bores and the thimbles having the shape shown in detail in Figs. 7 to 14, and each thimble being held in its pocket by a seating ring 67. Each thimble, near its lower end, has an internal peripheral bead 68 and each seating ring, near its upper end, has a similar bead 69, see Fig. 10. These beads present a circular opening of such diameter that a block 2 may be frictionally held thereby at one end or the other of a pocket 7.

A block 2 having been delivered by the chute 52 against the terminal block 38, the plunger 51 is operated to force the block through the guideway 8 and into the pocket 7 then in registry with the guideway at the block inserting station A (Fig. 4). The bead 68 holds the block in the pocket while the turret rotates a step and brings the block to the center-punching station B.

Attention is now directed to the formation of the slide 53 (Figs. 1, 5 and 6). The slide 53 is provided with a horizontal bracket 70 which supports, in addition to the block transerrer 51, a center-punch anvil 71 and a nailer anvil 72. The location of the two anvils and the block transerrer on the slide is on the arc of a circle the radius of which is the same as the radius of the circle passing through the centers of the turret pockets, and their angular spacing is the same as that of the pockets. When the block (Fig. 7) reaches station B the succeeding upward movement of the slide 53 causes the anvil 71 to engage the block and, due to the height of the anvil, force the block into engagement with the upper bead 69 of the pocket 7. The block is supported by the anvil 71 until the completion of the center-punching operation by the punch 73 which is attached to the slide 74 (Fig. 1) reciprocated in timed relation to the turret movements by a cam in a cam disk 75 on the shaft 36, all as described in said Patent No. 1,411,951.

The next step of the turret brings the punched block to the nailing station C (Fig. 4). The operation of the machine has previously caused the picker 76 (Fig. 1) to pick a nail from the raceway 77 and deposit it in the throat 78 (Fig. 3) below the nail driver 79. The raceway 77 is maintained full of nails by a nail delivering mechanism like that described and claimed in my said Patent No. 1,511,258. The nail-driver is attached to and operated by the center-punch slide 74, and the picker is operated by a cam in a cam disk 80 on the cam shaft 36, all as described in said Patent No. 1,411,951. Prior to a descent of the nail-driver the rise of the slide 53 has brought the nailer anvil 72 to a position flush with the lower face of the pocket 7 containing the punched block at its upper end, or projecting slightly within said pocket according to whether long or short nails are being fed. The subsequent descent of the nail-driver 79 places the point of the nail in the center punch 9 and then forces the nail and block downwardly within the pocket until the block engages the anvil 72. Thereupon continued pressure from the nail driver forces the point of the nail through the block and into the open end of the anvil 72, as shown in Fig. 9 for a long nail.

The reason for constructing the nail pockets with means for holding a block at

either the upper or lower end thereof will now be apparent. The nail must be driven so as to project from the block normal to its surface; otherwise the seat 3 will be mis-formed resulting in a crippled nail. If the nail, after leaving the throat 78, has to drop on the block there is danger of its being driven at an angle to the surface. By seating the block at the upper end of the pocket for the center-punching operation it is then presented to the nailer while in the same location, and the nail point enters the punch 9 before it escapes from the guiding influence of the nailing throat. Sufficient resistance is offered by the bead 69 and by the wall of the pocket, as the block descends under pressure from the nail-driver, to force the nail into the block slightly and hold it in its correct vertical position for the completion of the nail driving operation when the downward movement of the block is stopped by the anvil 72.

By driving the nail accurately and so that its point projects only a short distance through the block, accuracy in forming the head at the capping station is insured. In the machine of said Patent No. 1,411,951, where the nail was driven through the block until its head was seated in the punch 9, a very slight tilt on the nail caused it to be engaged by the upper end of the plunger 19 at the capping station resulting in a cripple. With the moderate projection of the nail provided by the present mode of operation this difficulty is wholly obviated.

From these considerations it will be understood that it is important that nails of both lengths be driven only partially through the block at the nailing station. It is convenient to so design the machine as to provide for the projection of either a long or a short nail below the lower surface of the block for the same distance. Accordingly the nailer anvil is made vertically adjustable in the bracket 70 of the slide 53. The anvil 72 is seated in a vertical bore in the bracket 70 the height of its upper end above the bracket being varied by removing a locking pin 81 (Fig. 3) from one of two transverse holes 82 in the bracket and slipping it into the other, the anvil meanwhile being moved vertically to bring a pin receiving recess at its lower end opposite the hole in which the locking pin is to be seated. The distance between the holes 82 is equal to the difference in length between the nails. Thus the block may always be supported within the pocket of the turret at an elevation to be penetrated equally by long or short nails forced therein by the nail-driver, which has a driving stroke of constant length.

A further new feature of the machine, which provides for the ejection of the first two nails driven from the throat 78 before a

130

block 2 reaches station C, will now be explained. The nailer anvil 72 is tubular and receives within it a nail ejector 83 (Fig. 3) which is secured by its lower end in a fixed bracket 84 fastened to the long bearing 23 of the shaft 28. Thus all nails driven from the throat 78, when the registering pocket 7 is empty, are received within the anvil 72 and when the slide 53 recedes the ejector 83 10 topples these nails from the end of the anvil 72.

The remaining steps in forming the nail are as already briefly described and as fully, described in said Patent No. 1,411,951. The 15 turret carries the assembled block and nail, as shown in Fig. 9, step by step to the capping station D. Meanwhile the feed rolls 85, driven by gearing from the shaft 28, as shown in Fig. 4, have advanced the insulating strip 86 in the guideway 11 ready to be cut into caps and compressed on the block in the die cavity 18. There is enough resistance offered by the dinked cap 5 (Fig. 11), to cause the block 2 to be slid on the 20 nail 1 until the head of the nail is seated in the center-punch 9, before the cap is forced into the restricted throat 17 of the dinker 13 (Fig. 12). After the nail is completely formed (Fig. 13) the ejector 21 topples the 25 nail into the chute 87 (Fig. 3) which directs it to a suitable container.

The dinker 13 and plunger 15 are operated from a cam in a cam disk 88 on the cam shaft 36, and the plunger 19 and ejector 21 30 are operated from cams 89 and 90, respectively, on said shaft, all in the same manner as described in said Patent No. 1,411,951. An additional feature has, however, been added to the prior machine to prevent breakage should a nail become jammed in the die cavity. The cam groove in the disk 88 imparts a constant throw to the slide 91 (Fig. 3) which actuates the plunger 15 and means 35 is provided to cushion the pressure from this cam should the plunger be prevented from reaching its lowest position. Accordingly the usual bell-crank 92 carrying the cam roll, connected to the slide by the link 93, is mounted on a floating pivot 94. The pivot 94 is received in the adjacent forked end of a horizontal lever 95 (Fig. 2) fulcrumed on a pin 96 held at one end by the frame 24 and at the other by a depending bracket 97. The other end of the lever 95 rests upon the 40 upper end of a coiled spring 98 carried by a headed rod 99 passing through a lug 100 on the frame and the end of the lever. The strength of the spring is determined by the usual adjusting nuts as shown in Fig. 2. 45 The effect will readily be understood. If the plunger 15 meets an obstruction, as soon as the pressure applied from the cam 88 becomes greater than the strength of the spring 98, the spring will yield causing the floating pivot to rise as the cam roll rises, the bell-

crank lever 92 and lever 95 pivoting as a single element on the pin 96.

The sequence of operations has been set forth in connection with the description of the features of the machine and attention need only be drawn to the fact that the turret and co-operating parts ensure the ejection of waste nails of varying lengths and also the transfer of such nails from the nailing station to the capping station without loss from the turret. With the construction described the capping station is continuously supplied with assembled nails and blocks thus making certain the rapid manufacture of completed nails, and while the present invention shows and describes a particular means to gain this end, which is convenient and readily controlled, it is comprehensive in this and other respects, as detailed in the appended claims, it being obvious that those skilled in the art may devise various mechanical devices to carry the invention into practical effect.

What is claimed as new, is:—

1. A machine for making insulated nails of the type described having, in combination, a rotary turret, mechanism for rotating said turret step-by-step, said turret having a series of peripherally arranged pockets presenting chambers which remain open at both ends throughout their travel, a device for supplying said pockets successively with blocks through one open end at each period of rest, means operating simultaneously with said block supplying device to support two previously supplied blocks for operations thereon through the other open ends of the pockets containing said blocks, and means for successively removing the blocks from the pockets and completing the formation of the nails. 90

2. A machine for making insulated nails of the type described having, in combination, a rotary turret, mechanism for rotating said turret step-by-step, said turret having a series of peripherally arranged pockets presenting chambers which remain open at both ends throughout their travel, a device for supplying said pockets successively with blocks through one open end at each period of rest, means movable toward and from said turret at each period of rest to support two previously supplied blocks for operations thereon through the other open ends of the pockets containing said blocks, and means for successively removing the blocks from the pockets and completing the formation of the nails. 95

3. A machine for making insulated nails of the type described having, in combination, a rotary turret, mechanism for rotating said turret step-by-step, said turret having a series of peripherally arranged pockets presenting chambers which remain open at both ends throughout their travel, a device 100

- for supplying said pockets successively with blocks through one open end, a slide for supporting said device, a pair of anvils also supported on said slide, means for advancing said slide to supply a block to one pocket and present the anvils in block-supporting position at two adjacent pockets previously supplied with blocks, and means for operating on the blocks so supported 10 by the anvils, said operations taking place at each period of rest of the turret.
4. A machine for making insulated nails of the type described having, in combination, a rotary turret, mechanism for rotating 15 said turret step-by-step, said turret having a series of peripherally arranged pockets presenting chambers which remain open at both ends throughout their travel, a device for supplying said pockets successively with 20 blocks through one open end at each period of rest, means operating simultaneously with said block supplying device to support two previously supplied blocks in other pockets, and means for center-punching the block 25 held at one pocket and driving a nail in the block held at the other pocket, said operations taking place at each period of rest of the turret.
5. A machine for making insulated nails 30 of the type described having, in combination, rotary turret, mechanism for rotating said turret step-by-step, said turret having a series of peripherally arranged pockets presenting chambers which remain open at 35 both ends throughout their travel, a device for supplying said pockets successively with blocks through one open end, a slide for supporting said device, a pair of anvils also supported on said slide, means for advancing 40 said slide to supply a block to one pocket and present the anvils in block-supporting position at two adjacent pockets previously supplied with blocks, and means for simultaneously center-punching and nailing said 45 two blocks.
6. In a machine for making insulated nails of the type described, an intermittently driven shaft, a nail carrying turret secured thereto comprising a disk-like structure having a series of peripheral block-receiving pockets, open at both ends, and means within each pocket for holding a block therein during the travel of the turret.
7. In a machine for making insulated 55 nails of the type described, an intermittently driven shaft, a nail carrying turret secured thereto comprising a disk-like structure having a series of peripheral block-receiving pockets, open at both ends, a thimble seated within each pocket constructed 60 to permit the block to pass therethrough, and means for holding each thimble in position.
8. In a machine for making insulated 65 nails of the type described, an intermittently driven shaft, and a nail carrying turret secured thereto comprising a disk-like structure having a series of peripheral block-receiving pockets, open at both ends, said pockets having means for supporting a block at either the upper or the lower end of the pocket.
9. In a machine for making insulated 70 nails of the type described, an intermittently driven shaft, a nail carrying turret secured thereto comprising a disk-like structure having a series of peripheral block-receiving pockets, open at both ends, and a thimble within each pocket constructed to permit the blocks to pass therethrough constructed to present a restricted opening near one face of the turret.
10. In a machine for making insulated 75 nails of the type described, an intermittently driven shaft, a nail carrying turret secured thereto comprising a disk-like structure having a series of peripheral block-receiving pockets, open at both ends, and a thimble within each pocket constructed to permit the blocks to pass therethrough having 80 a peripheral internal bead near one end thereof forming a restricted opening to the pocket.
11. In a machine for making insulated 85 nails of the type described, an intermittently driven shaft, and a nail carrying turret secured thereto comprising a disk-like structure having a series of peripheral block-receiving pockets, open at both ends, said pockets having means near the upper and 90 lower faces of the turret for holding a block frictionally at one end of the pocket.
12. In a machine for making insulated 95 nails of the type described, an intermittently driven shaft, a nail carrying turret secured thereto comprising a disk-like structure having a series of peripheral block-receiving pockets, open at both ends, means in the pockets for holding a block frictionally at 100 the ends thereof but loosely at the center, and means for supplying said pockets with blocks.
13. A machine for making insulated 105 nails comprising a nail and a block having, in combination, an intermittently rotating turret having a series of peripheral block-receiving pockets, means for supplying blocks successively to said pockets at a block-supplying station, means for simultaneously delivering nails at a nailing station beyond said block supplying station in the travel of the turret, and means for ejecting from the machine nails delivered to empty pockets at the start of the nail making operation.
14. A machine for making insulated 115 nails comprising a nail and a block having, in combination, a rotary turret having a series of peripheral nail-holding pockets, means for rotating the turret step-by-step, means 120 for operating during a period of rest for sup-

- plying a block to one pocket and means simultaneously delivering a nail to another pocket one or more stations beyond the pocket receiving the block, and means at the 5 nail delivering station for ejecting said nail from the machine before the block reaches said station through the travel of the turret in case the pocket receiving the nail is not supplied with a block.
- 10 15. A machine for making insulated nails comprising a nail and a block having, in combination, a rotary turret having a series of peripheral nail-holding pockets, means for rotating the turret step-by-step, means 15 operating during a period of rest for supplying a block to one pocket and means simultaneously delivering a nail to another pocket one or more stations beyond the pocket receiving the block, a hollow anvil at 20 the nail delivering station to receive said nail in case the pocket is not supplied with a block, and means for ejecting said nail from the anvil and the machine.
16. A machine for making insulated nails 25 comprising a nail and a block having, in combination, a rotary turret having a series of peripheral nail-holding pockets, means for rotating the turret step-by-step, means operating during a period of rest for supplying a block to one pocket and means simultaneously delivering a nail to another pocket one or more stations beyond the pocket receiving the block, an anvil movable into and out of position to support a 30 block at said nailing station and constructed to support the nail in case there is no block in the pocket, and means to eject said nail from the machine when the anvil is retracted from the pocket.
- 40 17. A machine for making insulated nails comprising a nail and a block having, in combination, a rotary turret having a series of peripheral nail-holding pockets, a block supplying station, a nailing station, means 45 for rotating the turret step-by-step to present the pockets successively to the block supplying station and the nailing station, means for supplying a block and means for supplying thereafter a nail to each pocket, a 50 nail-driver at the nailing station, and means for supporting the block at the nailing station in position to cause the driver to drive nails of different lengths into the block with equal penetration.
- 55 18. A machine for making insulated nails comprising a nail and a block having, in combination, a rotary turret having a series of peripheral nail-holding pockets, a block supplying station, a nailing station, 60 means for rotating the turret step-by-step to present the pockets successively to the block supplying station and the nailing station, means for supplying a block and means for supplying thereafter a nail to each 65 pocket, an anvil for supporting the block and a nail-driver, both at the nailing-station, and means for adjusting the anvil to support blocks in different locations within the pocket for driving nails of different lengths therein.
- 70 19. A machine for making insulated nails comprising a nail and a block having, in combination, a rotary turret having a series of peripheral nail-holding pockets, a block supplying station, a nailing station, means 75 for rotating the turret step-by-step to present the pockets successively to the block supplying station and the nailing station, means for supplying a block and means for supplying thereafter a nail to each pocket, 80 an anvil for supporting the block and a nail-driver, both at the nailing-station, and means for adjusting the anvil toward and from the nail driver to accommodate the driving of nails of different lengths into said 85 blocks.
20. A machine for making insulated nails comprising a nail and a block having, in combination, a nail-holding turret rotatable 90 step-by-step and having a series of peripheral pockets open at top and bottom, a slide below said turret carrying a block supplying plunger, and two anvils registering with three successive pockets, means for reciprocating said slide toward and from the turret 95 during periods of rest whereby said anvils are positioned to support blocks previously supplied to two of said pockets, and means for center-punching and nailing said two blocks while so supported.
- 100 21. A machine for making insulated nails comprising a nail and a block having, in combination, a nail-holding turret rotatable step-by-step and having a series of peripheral pockets open at top and bottom, a slide below said turret carrying a center-punch anvil and a nailing anvil registering with two adjacent pockets, said former anvil being nearer to the turret than the latter when in a position of rest below the turret, 105 and means for operating the slide to cause said center-punch anvil to enter a pocket and support the block supplied thereto at the upper end of the pocket while the nailing anvil supports the block in its pocket at 110 the lower end thereof.
- 110 22. A machine for making insulated nails comprising a nail and a block having, in combination, a nail-holding turret rotatable step-by-step and having a series of peripheral pockets open at top and bottom, means for supplying blocks to said pockets, two plungers below the turret registering with adjacent pockets constructed to support the blocks in said pockets one at the upper end and the other at the lower end thereof, and means for advancing said plungers into engagement with the blocks to so support them 115 during periods of rest of the turret.
- 120 23. A machine for making insulated nails 125

comprising a nail and a block having, in combination, a nail-holding turret rotatable step-by-step and having a series of peripheral pockets open at top and bottom, a slide below said turret carrying a block supplying plunger, and two anvils registering with three successive pockets, means for reciprocating said slide toward and from the turret during periods of rest whereby said anvils are positioned to support blocks previously supplied to two of said pockets, and means for center-punching and nailing said two blocks while so supported, said nailing anvil being hollow to permit the nailing means to drive the nail through the block and extend from the lower face thereof.

24. A machine for making insulated nails comprising a nail, a block and a cap having, in combination, means for driving a nail partially through a block, means for supplying a cap, and means for completing the driving of the nail through the block and applying the cap to the block.

25. A machine for making insulated nails comprising a nail, a block and a cap having, in combination, means at a nailing station for driving a nail partially through a block, means at a capping station for supplying a cap, means for transferring the nail and block to the capping station, and means at the capping station for forcing the nail completely into the block and moulding the cap on the block over the nail head.

26. A machine for making insulated nails comprising a nail, a block and a cap having, in combination, means at a nailing station for driving a nail partially through a block, means at a capping station for supplying a

cap, means for transferring the nail and block to the capping station, and means at the capping station for completing the driving of the nail through the block and moulding the cap on the block in one continuous operation.

27. A machine for making insulated nails comprising a nail and a block having, in combination, a nail-holding turret rotatable step-by-step and having a series of peripheral pockets open at top and bottom, means for supplying blocks successively to the upper ends of said pockets as each registers at a block-supplying station, means for delivering a nail to each block at a nailing station while the block is still retained at the upper end of the pocket, a nail-driver at said nailing station, and means for supporting each block at the lower end of the pocket for the nail driving operation.

28. A machine for making insulated nails comprising a nail and a block having, in combination, a rotatable nail-holding turret having a series of peripheral pockets open at top and bottom, means for supplying blocks successively to the upper ends of said pockets as each registers at a block supplying station, means for rotating said turret step-by-step to transfer the blocks to a center-punching station and then to a nailing station at which stations a center-punch and a nail-driver are respectively located, and means for retaining each block at the upper end of its pocket until it has been engaged by the nail to be driven therein at the nailing station.

CHARLES C. BLAKE.
